UNITED STATES PATENT OFFICE.

ALEXANDER MACMICHAEL AND CHARLES SCHINK, OF ASHLAND, KENTUCKY.

MEANS FOR CASTING INGOTS.

1,417,269.

Specification of Letters Patent. Patented May 23, 1922.

Application filed December 14, 1920. Serial No. 430,703.

To all whom it may concern:

Be it known that we, ALEXANDER MACMICHAEL and CHARLES SCHINK, citizens of the United States, residing at Ashland, in 5 the county of Boyd and State of Kentucky, have invented certain new and useful Improvements in Means for Casting Ingots, of which the following is a specification.

The object of this invention is to provide 10 simple and efficient means whereby the access of air to molten metal while the same is being poured into a mold will be prevented and a serious source of weakness in the finished product thus obviated. The invention provides means whereby the molten 15 metal may be transferred from the ladle to the mold by the force of gravity and the conveyer by which the transfer is effected may be shortened as the pouring proceeds 20 so that separation of the fluid particles will be prevented and a solid ingot free of air cells will be produced.

The invention is illustrated in the accompanying drawings and will be hereinafter 25 fully set forth.

In the drawings—

Figure 1 is a side elevation of our improved apparatus;

Fig. 2 is a transverse section of the same; 30 Fig. 3 is a plan view.

The mold 1 and the ladle 2 may be of any preferred or well-known form, the ladle being equipped with a bail or handle 3 whereby it may be suspended from a crane in the 35 usual manner, as will be readily understood. The ladle is also provided with an outlet opening 4 in its bottom and a stopper or valve 5 is fitted in the ladle and operated in the usual manner.

40 In embodying our invention in a metal pouring apparatus, we secure to the bottom of the ladle beams 6 which are disposed at opposite sides of the discharge opening 4, as clearly shown in Fig. 2, and extend laterally beyond one side of the ladle, as shown 45 clearly in Figs. 1 and 3. A nozzle or pouring spout is supported upon the beams 6 and consists of an upper section 7 which at its upper end is flared to fit close against the 50 bottom of the discharge opening and is provided with a lateral flange 8 resting upon the lower inwardly projecting webs of the beams 6 and has its lower end free of projections so that it may fit closely but slidably 55 within the lower section 9 of the spout. The said lower section 9 is expanded slightly

at its upper end, as shown at 10, to receive packing 11 which is compressed within the chamber produced by the expansion of the tube and around the upper section 7 by a 60 gland 12 which is carried by the lower tubular section 9 and is secured thereto by bolts 13 fitted through the annular flange 14 on the tubular section 9 and the flange 15 at the upper end of the gland. The flange 65 14 of the spout section 9 is so constructed as to project beyond the edge of the flange 15 and in its projecting portion is equipped with eyes 16 at diametrically opposite points in which are engaged the ends of cables 17. 70 These cables 17 extend upwardly from the flange 14 and are trained around guide pulleys 18 carried by the beams 6, as shown. From the guide pulleys 18, the cable extends to drums 19 which are secured upon 75 the ends of a shaft 20 which shaft is journaled in suitable bearings upon the beams 6 near the outer ends of the same, as shown. Upon the beams, adjacent the said shaft 20, we mount a small electric motor 21, the 80 shaft 22 of which is equipped with a pinion 23 meshing with a gear 24 secured upon the shaft 20 whereby when the circuit through the motor is closed and the motor thereby actuated the shaft 20 and the winding 85 drums 19 will be slowly rotated to wind the cables 17 and thereby raise the lower spout section 9. The said spout section 9 is provided near its lower end with an annular rib or flange 25 which is adapted to bear 90 upon the upper surface of the molten metal in the mold and thereby prevent splashing of the same so that the entrance of air into the liquid metal will be prevented and separation of the fluid particles overcome. 95

In operation, the fluid metal is delivered into the ladle in the usual manner, the stopper or valve 5 being in closed position. When the ladle and a mold have been brought into proper relative position the 100 spout section 9 is lowered in the mold until it touches or is close to the bottom thereof, after which the stopper is disengaged from the discharge opening and the metal permitted to flow through the spout into the 105 mold. When the level of the liquid in the mold reaches the flange or rib 25 at the lower end of the spout, the motor is started and the cables will be then wound so that the lower spout section 9 will be lifted as 110 the level of the metal in the mold rises and it will be understood, of course, that the

gearing whereby the motor is connected with the winding drum shaft will be timed so that the drums will rotate at a speed corresponding to the speed with which the 5 metal flows into the mold. The air which may be within the spout prior to the pouring of the metal is permitted to escape around the lower end of the spout and between the edge of the flange 25 and the end 10 walls of the mold, and the metal entering the mold will pass into the same out of direct contact with the air so that no air will be drawn into the metal to commingle therewith and separate the fluid particles. 15 The telescopic construction of the discharge spout or nozzle permits the same to be reduced in length as the metal rises in the mold and effectually guards against the entrance of air into the interior of the metal 20 inasmuch as the stream of metal is enclosed by the spout through its entire length. The gland 12 and packing 11 effectually prevent leakage of air between the sections of the discharge spout while at the same time permitting the free relative movement thereof. 25

Having thus described the invention, what is claimed as new is:

1. In an apparatus for casting ingots, the combination with a mold, and a ladle disposed above the mold, of a telescopic discharge spout carried by the ladle and adapted to enter the mold.
2. In an apparatus for casting ingots, the combination with a mold, and a ladle, of a telescopic discharge spout carried by the ladle to direct the metal into the mold, and means carried by the ladle for reducing the effective length of the said spout as the level of the metal in the mold rises.
3. In an apparatus for casting ingots, the combination of a ladle, a mold, a discharge

spout carried by the ladle and comprising an upper relatively fixed section and a lower section adapted to enter the mold but slidably fit upon the upper section, and means 45 carried by the ladle for raising the said lower section as the metal rises in the mold.

4. In an apparatus for casting ingots, the combination of a mold, a ladle, a discharge spout carried by the ladle and comprising an 50 upper relatively fixed section and a lower section slidably fitted upon the upper section and adapted to enter the mold, the upper end of said lower section being expanded, packing fitted in the expanded portion of the 55 lower section, a gland carried by the lower section and compressing said packing around the upper section, and means carried by the ladle for raising the lower section as the metal rises in the mold.

5. In an apparatus for casting ingots, the combination of a mold, a ladle, spaced beams secured to the bottom of the ladle at opposite sides of the discharge opening therein and extending laterally beyond the ladle, a 65 telescopic discharge spout carried by said beams in alinement with the discharge opening in the ladle, guide pulleys upon said beams, a winding shaft mounted upon the outer portions of the beams, a motor supported on the beams and operatively connected with said winding shaft, drums secured on said shaft, and cables attached to said drums and to the lower section of the telescopic discharge spout and having their 70 intermediate portions trained over the said guide pulleys.

In testimony whereof we affix our signatures.

ALEXANDER MacMICHAEL. [L. S.]
CHARLES SCHINK. [L. S.]
